UNITED STATES PATENT OFFICE.

GEORGE A. SCHOBERT, OF RACINE, WISCONSIN.

TRUNK.

No. 823,140.

Specification of Letters Patent.

Patented June 12, 1906.

Application filed November 4, 1905. Serial No. 285,914.

To all whom it may concern:

Be it known that I, GEORGE A. SCHOBERT, a citizen of the United States, residing at Racine, in the county of Racine and State of Wisconsin, have invented certain new and useful Improvements in Trunks; and I do hereby declare the following to be a full, clear, and exact description of the invention, such as will enable others skilled in the art to 10 which it appertains to make and use the same.

My invention relates to trunks; and its object is to provide a device of this character having a tray adapted to be automatically 15 raised when the trunk is opened and which can be very easily removed from the trunk when in such position.

A still further object is to provide a tray which can be swung upward into the trunk-20 lid and locked in a novel manner, so that access may be had to the interior of the trunk.

With the above and other objects in view the invention consists of a tray which is detachably mounted upon supporting-strips 25 which are connected to the trunk-lid and are mounted upon links connected to the trunk-body. These strips and links are so disposed that when the lid is raised the tray is carried upward out of the body by the strips and 30 swung backward into the lid.

A drawer is supported in the lower portion of the tray and is adapted to project backward therefrom, so that the entire tray may be swung upward, if desired, when the trunk 35 is opened and the drawer slid downward into engagement with the trunk-body and lock the tray in raised position.

The invention also consists of certain other novel features of construction and combination of parts, the preferred form whereof will be hereinafter more clearly set forth, and pointed out in the claims.

In the accompanying drawings I have shown the preferred form of my invention.

In said drawings, Figure 1 is a vertical section through the closed trunk and showing the tray in end elevation. Fig. 2 is a similar view showing the trunk open. Fig. 3 is a plan view of the trunk and tray when in the 50 position shown in Fig. 2, the lid being shown in section. Fig. 4 is a view similar to Fig. 2 and showing the tray locked in an upright position. Fig. 5 is a section on line $z-z$, Fig. 2; and Fig. 6 is a section on line $y-y$, Fig. 2.

Referring to the figures by numerals of reference, 1 is the body of a trunk having a lid

2 hinged thereto in the ordinary manner, and extending upward from the ends of body 1 are links 3, which are pivoted at one end to the trunk-body and at the other end to supporting-strips 4. These supporting-strips 4 are pivotally connected to the lid 2 by means of pins 5, and the pivot-pin 6, which connects each supporting-strip 4 with its link 3, has a collar 7 and a head 8 at its inner end. Another pin 9, which is similar in construction to pin 6, extends inwardly from each supporting-strip near its pivot 5. The head 8 of pin 6 is adapted to project into a socket 10, formed in a plate 11, secured in any suitable manner to one side of the tray 12. This socket has a slot 13 extending vertically and of sufficient size to receive the collar 7. Another plate 14, constructed similarly to plate 11, is secured to each end of the tray 12, near 70 the rear thereof; but the slot of the socket in this plate is disposed horizontally instead of vertically, as is the slot in plate 11. The socket in the plate 14 is adapted to receive the head of the pin 9. The bottom of the 75 tray 12 is located adjacent the center thereof, as shown at 15; and at the lower edges of the end walls of the tray are disposed cleats 16, which support a drawer 17. This drawer is slightly longer from front to rear than the 80 tray, and its ends are beveled, and the front end has laterally-extending wings 18 for limiting the rearward movement of the drawer. Each link 3 and strip 4 are so disposed in relation to each other that the supporting- 85 strips 4 are maintained at all times in horizontal positions. When the trunk is closed, as shown in Fig. 1, the tray rests close to the front wall thereof, while the rear end of the drawer contacts with the opposite wall of the 90 trunk-body 1. When the lid 2 is raised, it pulls the links 3 and the supporting-strips 4 upward and backward, and therefore the rear end of the drawer 17 is pressed forward 95 by reason of its contacting with the rear wall of the trunk-body, while at the same time the tray is carried backward and upward. The entire tray will be swung from the rear edge of the trunk-body, and its rear end will be moved into the lid, as shown in Fig. 2, and in 100 the meantime the drawer 17 is pushed forward from the front of the tray, so that the same can be conveniently grasped and pulled open. The backward movement of the tray and the lid is limited by ears 19, which are 105 formed upon the ends of the strips 4 and overlap the links 3. Should it be desired to 110

remove the tray, it is merely necessary to first lift the front portion thereof, so that the plates 11 will be disengaged from pins 6, after which the tray can be pulled forward to dis- 5 engage it from the rear pins 9.

In order to allow of better access to the interior of the trunk-body, the tray can be swung upward in the lid, as shown in Fig. 4. This is done by simply swinging it backward 10 on the plates 14 and pins 9 and allowing the rear end of the drawer 17 to drop downward and overlap and engage the rear wall of the trunk-body. The entire tray is thus locked in raised position and cannot be lowered ex- 15 cept by pulling the drawer upward, so as to disengage its rear end from the trunk-body. When the trunk is closed, the vertically-projecting portion of the drawer 17 will come in contact with the front wall of the body 1, and 20 as the tray descends into its lowered position the tray will be shoved backward into the position disclosed in Fig. 1.

It will be seen that this trunk is very simple and compact in construction, and as there 25 are very few parts employed in the mechanism for raising and locking the tray there is practically nothing to get out of order.

If desired, the lower tray or drawer can be dispensed with, and in that event the single 30 tray can be held in a raised position by swinging it up and back into the cover 2 and past its center of gravity, as shown by dotted lines in Fig. 4.

Having thus fully described my invention, 35 what I claim as new, and desire to secure by Letters Patent, is—

1. The combination with a trunk having a movable lid, of a tray, means interposed between the trunk and lid for movably support- 40 ing the tray, said tray being pivotally mount-

ed upon said means, and a drawer connected to the tray and adapted to lock the same in raised position.

2. The combination with a trunk having a movable lid, of supporting devices pivotally connected to the trunk and lid respectively, a tray detachably and pivotally mounted upon the supporting devices, and a drawer connected to the tray adapted to engage the trunk and support the tray in raised position.

3. The combination with a trunk having a movable lid, of a tray within the trunk, means operated by the lid for raising the tray, and a drawer supported by the tray and adapted to contact with opposite walls of the trunk when the tray is raised or lowered and to be shifted backward and forward thereby.

4. The combination with a trunk having a movable lid, of a tray within the trunk, means operated by the lid for raising or lowering the tray, said tray being pivotally mounted upon said means, and a drawer mounted within the tray and adapted to engage the trunk to hold the tray in raised position.

5. The combination with a trunk having a movable lid, of supporting-strips pivoted to the lid, links pivoted to the trunk and strips, the ends of said strips having lateral extensions adapted to overlap the links and limit the movement of the lid, a tray, sockets secured upon the tray and socket-engaging devices extending from the supporting-strips.

In testimony whereof I have signed my name to this specification in the presence of two subscribing witnesses.

GEORGE A. SCHOBERT.
